UNITED STATES PATENT OFFICE.

CHARLES A. HULTQUIST, OF LOS ANGELES, CALIFORNIA.

FLUID-OPERATED TOOL.

1,342,540.

Specification of Letters Patent.

Patented June 8, 1920.

Application filed March 24, 1919. Serial No. 284,793.

To all whom it may concern:

Be it known that I, CHARLES A. HULTQUIST, a citizen of the United States, residing at Los Angeles, in the county of Los Angeles and State of California, have invented a new and useful Fluid-Operated Tool, of which the following is a specification.

This invention relates to tools of the character operated by a fluid such, for instance, as compressed air and an object of the invention, in general, is to provide a tool of this character having maximum efficiency.

Another object of the invention is to so construct the tool that the hammer will deliver its blow when traveling at maximum speed.

Another object is to avoid waste of the operating fluid by so constructing the tool that the compressed fluid employed in operating the valve, which controls the reciprocative movement of the hammer, will, after opening the valve, pass into the cylinder to operate the piston.

Another object is to so construct the tool that the valve will not be kept from properly seating by scale or the like from the fluid supply pipe.

Another object is to make provision for the reduction of pressure in front of the hammer, as it delivers its blow, to substantially that of the atmosphere.

Other objects and advantages will appear in the subjoined detailed description.

The accompanying drawings illustrate the invention.

Figure 1 is a side elevation of a fluid operated tool constructed in accordance with the provisions of this invention.

Fig. 2 is an enlarged elevation, mainly in vertical mid section, of the tool shown in Fig. 1, portions of the handle and drill steel being broken away to contract the view.

Figs. 3, 4 and 5 are plan sections on lines indicated by x^3-x^3 , x^4-x^4 and x^5-x^5 , respectively, Fig. 2.

Fig. 6 is a fragmentary sectional elevation of a modified form of the invention.

There is provided a cylinder comprising a portion 1 of larger inside diameter and a portion 2 of smaller inside diameter, the portion 1 forming a chamber for the hammer or head 3 of a piston 4 which works in the cylinder portion 2. The cylinder is partly formed in a barrel 5 and partly in a

head 6, which may be termed the rear head. The barrel 5 at its forward end is closed by a front head 7 which may be a separate member, if desired by the constructor. The head 7 is tubular and in the bore 8 thereof is accommodated the head 9 of the drill steel 10, said head projecting into the barrel 5 in a reduced portion 11 adapted to receive the blow delivered by the hammer 3. The drill steel 10 passes through the bore 12 of a drill steel retainer 13. The head 9 is preferably separate from the body of the drill steel so as to form an anvil block or tappet.

Any suitable means may be employed for fastening the barrel 5, heads 6, 7 and drill steel retainer 13 together to hold them assembled and such means, for example, may be constructed by providing the head 6 and drill steel retainer 13 with laterally projecting ears 14 through which bolts 15 pass so as to clamp the barrel 5 and head 7 between the head 6 and retainer 13. The barrel 5, heads 6, 7 and retainer 13 all together constitute the body of the tool. The head 7 may be provided with an annular shoulder 16 adapted to fit the bore of the barrel 5, and the steel retainer 13 may also be provided with an annular shoulder 17 adapted to fit the bore 8 of the head 7.

The body is provided with a duct, one branch 18 of said duct opening into the rear end of the cylinder portion 2 and the other branch 19 opening into said cylinder portion adjacent the cylinder portion 5. When the piston 4 is in the retracted position shown in Fig. 2 the outlet end of the duct branch 19 is adjacent a reduced portion 20 of the piston so that the operating fluid entering said duct from the supply line, not shown, will discharge into the cylinder portion 2 and thence behind the hammer 3. The cylinder portion 5 is provided with an exhaust port 21 located substantially midway of the length of the cylinder portion 5.

Substantially midway of the cylinder portion 2 is a port 22 opening into a valve chamber 23 which forms a portion of the barrel 5 and which contains a sliding tubular valve 24. Adjacent the port 22 the tubular valve 24 is provided with a reduced portion 25 of less diameter than the bore portion 27 of the valve chamber so that the operating fluid entering the port 22 from the cylinder portion 2 will press upon an annular shoulder 26 of the valve, said shoulder 100

105

110

fitting the valve chamber portion 27. The valve chamber portion 27 is of larger diameter than the other portions of the valve chamber. The valve is provided with another shouldered portion 28 which fits a valve chamber portion 29 of smaller diameter than the portion 27, and a reduced portion 30 of the valve fits a reduced portion 31 of the valve chamber. Opening into the portion 29 of the valve chamber is a duct 32 which communicates with the duct branch 18 so as to admit the operating fluid to the portion 29 of the valve chamber. The valve 24 is provided with a relatively small relief port 33 opening from the periphery of the valve to the bore 34 thereof.

The valve chamber portion 27 is provided with a duct 35 opening into a duct 36, one end of the duct 36 communicating with the atmosphere at the periphery of the body of the tool and the inner end of the duct 36 communicating with the portion 31 of the valve chamber. The reduced portion 30 of the valve is provided with an annular groove 37 which registers with the duct 36 when the valve 24 is at the outer end of its movement as shown in Fig. 2 of the drawings. When the valve 24 is at the inner end of its movement the groove 37 is out of communication with the duct 36 and thus the valve functions to close the duct 36.

Communicating with the valve chamber in the form of the invention shown in Figs. 1 to 5, at the reduced portion 31 thereof, is a duct 38, said duct being adapted to communicate with the annular groove 37 of the valve, especially when said valve is in its outermost position. The duct 38 communicates with the cylinder portion 5 at a point adjacent or somewhat above the level of the inner end of the drill head 9.

Opening from the inner or forward end of the valve chamber 23 to the cylinder portion 5 adjacent the head 7 is a duct 39, the outlet end of said duct being below the level of the inner end of the head 9 of the drill steel so that when the hammer 3 is in contact with the head 9 the operating fluid can flow into the cylinder portion 5 in front of the hammer 3. In Fig. 2 when the hammer 3 is in contact with the drill head 9, the hammer closes the intake end of the duct 38 so that fluid pressure at the front of the hammer will not be reduced by leakage of air through the duct 38, which, however, is otherwise controlled by means hereinafter to be described.

The valve chamber 23 may be closed at its rear end by a plug 40 screw-threaded into the barrel 5 flush with the outer end of said barrel. The head 6 may be provided with a suitable handle formed, in this instance, by a bar 41 extending through an eye 42 of the head 6.

Now referring particularly to the modi-

fication shown in Fig. 6 of the drawings, the parts analogous to those described above are indicated by the same reference characters used to designate the same parts in the form of the invention shown in Figs. 1 to 5, and all the features previously described are present in this form with the exception of the duct 38 which is omitted. In lieu of said duct the valve 24 is provided with a port 43 opening from the bore 34 of the valve into the groove 37 so that when the valve is in the position shown in Fig. 6 air can escape from the bore of the valve to the groove 37 and thence through the duct 36 to the atmosphere.

Assuming that the duct 18, 19 is connected with an operating fluid supply, the operation of the invention is as follows: It may be assumed at the start that the parts are in the positions shown in Fig. 2 of the drawings. The operating fluid flows from the supply pipe, not shown, into the duct branch 18, thence to the rear or constant pressure face 44 of the piston 4 and the operating fluid also flows through the duct branch 19 to the cylinder behind the forward or intermittent pressure face 45 of the piston. The pressure of the operating fluid drives the piston on its outer or striking stroke and as soon as the reduced portion 20 of the piston 95 passes out of registration with the duct branch 19 the piston 4 will cut off the supply of operating fluid from the rear pressure face 45 of the piston.

The piston 4 will continue on its striking stroke and when the rear pressure face 44 of the piston has passed by the port 22 the operating fluid in the cylinder portion 2 will discharge through the port 22 into the valve chamber portion 27 and press upon the shoulder 26 so as to move the valve 24 on its forward or port-opening stroke. It is to be noted that the plug 40, which forms one end of the valve chamber, is provided with a recess 46 in which the valve 25 seats when said valve is at the end of its port-closing stroke, as in Fig. 2. The valve 24 thus has a certain amount of "lap" so that the opening by the valve of the port 22 will occur after the valve has attained maximum speed, thus allowing a maximum amount of operating fluid to quickly flow into valve bore 34 after the valve has started to unclog the port 22. The port 22 is so positioned relatively to the face 44 of the piston, and the lap of the valve is made of such amount that the operating fluid entering the valve and flowing therethrough into the duct 39 will begin to discharge from the duct 39 into the cylinder portion 5 just at the moment, but not before, the hammer 3 strikes the drill head 9. Before the operating fluid however, thus discharges into the cylinder in front of the hammer 3, the hammer has passed the port 21 which permits the oper-

ating fluid in that portion of the cylinder to the rear of the hammer to escape to the atmosphere.

As the hammer 3 continues to move toward the drill head 9, after passing the port 21, said hammer tends to compress the fluid that is in front of it in the gradually diminishing space in front of the hammer between said hammer and the head 7. In prior tools of this description this fluid pressure is not relieved after closing of the exhaust port and consequently it forms a cushion to soften or minimize the force of the blow of the hammer upon the drill head, and therefore the drill steel does not deliver as hard a blow on the material being drilled as would result if the blow of the hammer 3 were not so cushioned. In the form of this invention shown in Figs. 1 to 5, however, the air being compressed in front of the hammer is forced from that portion of the cylinder in front of the hammer through the duct 38, thence into the valve chamber 23 and from said valve chamber through the duct 36 to the atmosphere, the valve 24 not having moved into position to close the duct 36 until the hammer 3 almost reaches the drill head 9. Thus practically all of the pressure in front of the hammer 3 is eliminated before the hammer strikes the drill head. As soon as the valve 24 has moved into port-opening position, it is clear that the portion 30 of the valve functions to close the duct 36, so that the operating fluid discharging from the duct 39 into the cylinder in front of the hammer 3 cannot escape by way of the duct 38 to the atmosphere.

As above noted the operating fluid discharges from the duct 39 into the cylinder in front of the hammer substantially at the moment that said hammer strikes, the drill head 9, and consequently the pressure of the operating fluid against the front face 47 of the hammer, as said hammer is brought to a stop against the drill head, will retract the piston or move it on its idle stroke away from the drill head 9. This movement of the piston is effected in spite of the fact that the compressed air has access to the face 44 of the piston since the area of the rear pressure face 44 is less than the area of the front pressure face 47 of the piston. As the piston returns, it shuts the port 22 so as to shut off the operating fluid from said port and the piston opens the exhaust port 21 thus relieving the pressure in the duct 39, valve bore 34 and port 22, and consequently the pressure of the operating fluid inducted to the valve chamber through the duct 32 will operate against the valve shoulder 28 so as to return the valve to the port-closing position shown in Fig. 2. When said valve begins to enter the recess 46, it of course cuts off the escape of operating fluid from that portion of the valve chamber between

the shoulder 26 and plug 40 but, owing to the provision of the duct 33, any remaining pressure that would tend to prevent perfect seating of the valve in the recess 46 will be eliminated through the duct 33. Any tendency to scale and other particles interfering with closing of the valve is overcome by reason of the sliding contact of the valve on the sides of the recess 46. It may here be noted that when the valve 24 moves forwardly and rearwardly it is not retarded in said movement by any tendency to increase or reduction of air pressure in that portion of the valve chamber between the shoulder 26 and shouldered portion 29 of the valve chamber, since the pressure will be kept at that of the atmosphere because of the presence of the duct 35 which allows outflow and inflow of air as the valve moves forwardly and rearwardly respectively. 85

When the piston has been retracted sufficiently far to uncover the discharge end of the duct 19, the operating fluid will again enter the cylinder behind the piston face 45 so as to again drive the piston on its striking stroke, and the reciprocation of the piston will thus continue as long as the operating fluid is admitted to the duct 18, 19.

In the modified form of the invention shown fragmentarily in Fig. 6, it is clear that the operation is the same as above described for the form of the invention shown in Figs. 1 to 5 excepting that, instead of the fluid pressure in front of the hammer 3 being relieved through the duct 38, the compressed fluid will flow from the cylinder portion in front of the piston through the duct 39 to the valve bore 34, thence through the port 43 to the valve chamber portion 31 and thence through the duct 36 to the atmosphere. 105

It is noted that the shoulder 28 forms a constant pressure face and is of less area than the intermittent pressure face formed by the shoulder 26, and that therefore the valve will be moved into port-closing position as soon as the piston closes over the port 22 and opens the port 21. The difference in areas of the shoulder 28 and shoulder 26 is a factor in the determination of the time of admission of the operating fluid into the cylinder in front of the piston since said difference governs the speed of travel of the valve under any given fluid pressure. Other factors which determine the time of admission of the operating fluid to the cylinder are the position of the port 22 with reference to the face 44 of the piston and the rear end of the valve, and the amount of lap of the valve. 115

From the foregoing it is clear that the construction provided by this invention eliminates back pressure on the piston during the striking stroke of the piston; that the fluid operating the valve to port-opening 130

- position is not wasted but is employed subsequently in the cylinder to retract the piston; and that the valve performs the double function of controlling the admission of operating fluid to the cylinder in front of the piston and the exhaust of a portion of said operating fluid from in front of the piston during the latter part of the working or striking stroke of the piston.
- 10 It is to be noted that the construction described above provides against any waste of the operating fluid for, when the piston moves on its back stroke to close the port 22, the compressed fluid caught in the port 22 passes from said port through the relief port 33, valve bore 34 and duct 39 to the cylinder in front of the piston, and such fluid therefore becomes effective to aid in moving the piston on its back stroke. Furthermore with this construction the compressed fluid first operates to open the valve and thereafter this same fluid flows through the bore of the valve and, the duct 39 being axially alined with the valve bore, the fluid flows directly from the valve bore into the duct 39 and thence to the cylinder.
- 15 20 25

30 The invention is not limited in its broader aspects to the exact details of construction described above and shown in the drawings, and therefore it is understood that the invention includes such changes and modifications as lie within the spirit and scope of the appended claims.

I claim:

- 35 1. A fluid operated drill comprising a cylinder having an exhaust port, a piston in the cylinder adapted to open and close the exhaust port, there being a valve chamber provided with an inlet port communicating 40 with the cylinder, said inlet port being opened and closed by the piston, a tubular valve in the valve chamber provided with a shoulder to receive pressure from the fluid admitted through the inlet port, said inlet 45 port being adjacent one end of the valve chamber, there being a duct axially alined at its intake end with the valve bore and connected with the front end of the cylinder and there being a duct to admit operating 50 fluid to the cylinder rearwardly of the piston.

- 55 2. A fluid operated drill comprising a cylinder having an exhaust port, a piston in the cylinder adapted to open and close the exhaust port, there being a valve chamber provided near its rear end with an inlet port communicating with the cylinder, the inlet port being adapted to be opened and closed by the piston, a tubular valve in the 60 valve chamber provided with a shoulder to receive pressure on its rear face from the fluid admitted through the inlet port, there being a recess at the rear end of the valve chamber adapted to receive the rear end of 65 the valve to close the rear end of said valve,

there being a relief port opening from the valve bore between the shoulder and the rear end of the valve, there being a duct opening from the front end of the valve chamber and communicating with the front end of the cylinder and there being a duct to admit operating fluid to the cylinder rearwardly of the piston.

3. A fluid operated drill comprising a cylinder having an exhaust port, a piston in the cylinder adapted to open and close the exhaust port, there being a valve chamber provided near its rear end with an inlet port communicating with the cylinder, the inlet port being adapted to be opened and closed by the piston, a tubular valve in the valve chamber provided with a shoulder to receive pressure on its rear face from the fluid admitted through the inlet port, there being a duct opening from the front end of the valve chamber and communicating with the front end of the cylinder, there being a duct to admit operating fluid to the cylinder rearwardly of the piston, the valve having a second shoulder and there being a duct to admit operating fluid to the valve chamber in front of the second shoulder, and the inlet port being the sole admission passage for the fluid operating the piston on its back stroke.

4. In a fluid operated drill, a cylinder, a piston in the cylinder, there being a duct to admit an operating fluid to the cylinder rearwardly of the piston, there being a valve chamber having a port opening into the cylinder to admit the operating fluid from in rear of the piston to the valve chamber, said port being controlled by the piston, and a tubular valve controlling the flow of the fluid from the valve chamber into the bore of the valve and forming a conduit for the fluid admitted through the port, and there being a duct to convey the fluid from the valve chamber to the front portion of the cylinder.

5. A fluid operated drill having a cylinder forming a piston chamber and a valve chamber and having a port establishing communication between one end of the piston chamber and valve chamber and a duct establishing communication between the opposite end of the piston chamber and valve chamber, a piston in the piston chamber controlling the port, and a tubular valve in the valve chamber closing said port when in one position and functioning as a movable conduit to establish communication between the port and duct when moved to a reverse position.

Signed at Los Angeles, California, this 17th day of March, 1919.
